O. J. Smith,

Atty.

UNITED STATES PATENT OFFICE.

ORSON J. SMITH, OF FARMER CITY, ILLINOIS.

SCREEN FOR SCREENING POTATOES.

SPECIFICATION forming part of Letters Patent No. 293,368, dated February 12, 1884.

Application filed December 3, 1883. (No model.)

To all whom it may concern:

Be it known that I, ORSON J. SMITH, of Farmer City, in the county of DeWitt and State of Illinois, have invented certain new and useful Improvements in Screens for Screening Potatoes; and I do hereby declare the following to be a full, clear, and exact description of the invention, such as will enable others skilled in the art to which it pertains to make and use it, reference being had to the accompanying drawings, which form part of this specification.

My invention relates to an improvement in screens for screening potatoes; and it consists, first, in the combination of the side pieces, end pieces, and screw-threaded rods, the end pieces at the lower end of the screen being provided with shoulders to prevent the rods from turning while the nuts are being tightened upon their opposite ends; second, in the combination of the upper screen, legs to support it at one end, and a trestle at the other, with the lower screen having its surface inclined toward one side, and provided with the opening through one side near its lower end, whereby potatoes of different sizes are deposited at the front and rear of the trestle; third, in the combination of the upper screen, the supporting-legs for its upper ends, the trestle for supporting its lower end, and which is provided with means for keeping the end of the screen in place, the lower screen removably attached to the upper one, and having its surface inclined toward one side and provided with an opening for the escape of the potatoes at the rear of the trestle, all of which will be more fully described herein-after.

The object of my invention is to provide a screen by means of which potatoes can be cleaned from all dirt, and the large ones separated from the small ones rapidly and easily.

Figure 1 is a vertical longitudinal section of a screen embodying my invention. Fig. 2 is a side view of the screen and its attachments. Fig. 3 is a vertical cross-section through the two screens, taken on the lines *a b* of Fig. 1.

The trestle, which is used to support the lower end of the screens, consists of the runners *A*, from which rise the inclined stands *B*, which are joined together at their up-

per ends by means of the horizontal piece *C*. Upon the top of this horizontal piece *C* is secured the strip *D*, against which the lower end of the upper screen bears for the purpose of preventing the screen from slipping off of the top of the trestle. Suitable notches, *c*, are formed in the rear side of this piece *D* to receive the ends of the screen, and thus prevent any sidewise movement. To the front side of the trestle are nailed suitable boards, *E*, to prevent the larger potatoes from running backward under the trestle, and to prevent the smaller potatoes from running forward and mixing with the larger ones. The runners *A* are used for the purpose of enabling the trestle to be readily hauled from one place to another. Where the potatoes are to be run directly into the cellar this trestle-work may be dispensed with, and the lower end of the upper screen may then be connected to the window or an opening of any kind in the side of the house, so that the potatoes may run directly into the cellar, and thus save the trouble of handling them twice.

The upper screen, *F*, is supported at its upper end by means of the pivoted legs *G*, which may be moved back and forth according as it is desired to incline the screens at a greater or less angle. This top screen, *F*, consists of the side pieces, *H*, which are of any suitable width, and which are connected together at their upper ends by means of the two cross-pieces *I*, which are separated just far enough, as shown in Fig. 3, to allow the metallic or wooden rods *J* to pass between them. The lower ends of the side strips are also secured together by means of two cross-pieces, *L*, which are also separated a sufficient distance to allow the rods *J* to pass between them, and each piece *L* is provided with a shoulder or rabbet, *d*, for the heads upon the rods to catch against, and thus prevent the rods from turning while the nuts are being screwed upon their upper ends. The rods by this construction are made not only removable from the screen, to be repaired in case they should become bent or broken, but are made adjustable laterally in regard to each other, so as to increase or decrease the space between them, and thus regulate the size of potatoes which shall drop through upon the

lower screen. By thus making the rods removable and adjustable, the size of the potatoes will be regulated at will. The upper edge of the upper one of the two cross-pieces L is 5 beveled, so as to allow the potatoes to readily pass over it. Also secured between the lower ends of the side pieces, and in a line with the top edge of the top piece L, is the board N, which serves to guide the potatoes down over 10 the top of the trestle. Potatoes of different sizes, and which are mixed more or less with dirt when thrown upon this upper screen, screen themselves as they rundown the incline plane which is formed by the rods J. All of 15 the dirt and the smaller potatoes drop through upon the lower screen, while the larger ones pass down over the front of the trestle. The screen is fastened at its lower end to the top of the trestle by means of the hooks O.

20 Fastened to the under side of the upper screen by means of hooks e or other suitable devices is a lower screen, P, the rods or bars Q of which are separated a suitable distance apart. These rods Q are supported by the 25 end pieces, S, of the frame, and by the cross-pieces S'. Instead of placing these rods upon a level, they are made to incline either toward one or both sides, as may be preferred. By inclining the rods toward one or both sides, 30 the potatoes are made to run toward the sides of the screen as they move down the incline plane, and when they reach its lower end they pass off through the openings T, which are made through the side pieces for that purpose.

35 Instead of catching against the end of the screen and remaining in the screen, they at once pass out through the openings T upon the ground in the rear of the trestle. As the board upon the front of the trestle prevents 40 the smaller potatoes from mingling with the

large ones, it will be seen that two piles of potatoes are formed, the larger ones being thrown to the front of the trestle, while the smaller ones drop in behind.

If so desired, the upper screen, which is 45 longer than the lower one, may be made to incline toward one or both sides, as shown by the lower screen, in which case, instead of having the potatoes pass directly to the front of the trestle, they would be passed off through 50 a suitable opening made in one or both of the side pieces.

Having thus described my invention, I claim—

1. In a potato-screen, the combination of the 55 side pieces, H, end pieces, I L, and screw-threaded rods J, the pieces L being provided with the shoulders d, substantially as shown.

2. The combination of the upper screen, legs to support it at one end, and a trestle at 60 the other, with the lower screen having its surface inclined toward one side, and provided with the opening T through one side near its lower end, whereby potatoes of different sizes are deposited at the front and rear of the trestle, 65 substantially as described.

3. The combination of the upper screen, the legs G, the trestle provided with means upon its top to keep the end of the upper screen in place, and the lower screen, P, removably attached to the upper one, and having its surface inclined toward one side, and provided with the opening T through one side, substantially as 70 set forth.

In testimony whereof I affix my signature in 75 presence of two witnesses.

ORSON J. SMITH.
